C. MOHME,
POISON BOTTLE,
APPLICATION FILED FEB. 28, 1920.

1,355,161.

Patented Oct. 12, 1920.

Inventor:

Charlie Mohme,
By J. L. B. *Atty*

UNITED STATES PATENT OFFICE.

CHARLIE MOHME, OF BRAWLEY, CALIFORNIA, ASSIGNOR OF ONE-HALF TO ANDREW KULAS, OF BRAWLEY, CALIFORNIA.

POISON-BOTTLE.

1,355,161.

Specification of Letters Patent. Patented Oct. 12, 1920.

Application filed February 28, 1920. Serial No. 362,146.

To all whom it may concern:

Be it known that I, CHARLIE MOHME, a citizen of the United States of America, and resident of Brawley, Imperial county, California, have invented a new and useful Improvement in Poison-Bottles, of which the following is a specification.

The object of this invention is to provide an improved construction for bottles or containers adapted to contain poison and so made and arranged as to limit the probability of accidental and uninformed use of the contents thereof, or the use thereof by children or feeble-minded persons.

15 My invention consists in the construction, arrangement and combination of elements hereinafter set forth, pointed out in the claims and illustrated by the accompanying drawing, in which—

20 Figure 1 is a side elevation of a complete container embodying my improvements. Fig. 2 is a vertical section on one diameter of the same. Fig. 3 is a bottom view of the same. Fig. 4 is a view of a pull-key 25 employed to operate devices on the container.

In the construction of the device as shown the numeral 10 designates a container or bottle, preferably made of glass, of generally cylindrical form throughout its major portion and formed with an integral contracted neck portion 11 and an integral stopper-simulating portion 12 at the apex of the neck portion. The bottom of the 35 container preferably is relatively thick and heavy and is formed with a slide-seat diametrically arranged and opening through the side thereof. The bottom also is formed with a central opening adapted to be closed

40 by a stopper 13, of suitable material such as cork, and the upper surface of said bottom inclines from all sides toward said opening. The bottom of the container also is formed with a radial groove 14, having an inclined

45 upper wall, and a lug 15 is formed on the wall of said container and closes the outer end of said radial groove. A closing plate 16 is slidably mounted in the seat in the bottom of the container and the outer end 50 of said plate is formed with a flange 17 adapted to be engaged by a hand of the user for manipulation of the plate relative to the slide seat. A leaf-spring latch 18 is mounted on one face of the plate 16 and is connected at one end by a rivet 19 to the central por-

tion of said plate. The latch 18 is of a length providing that when the plate 16 is fully seated the outer end thereof will enter the groove 14 and abut the lug 15 and prevent accidental removal of the latch 60 and plate from the slide seat. The spring latch 18 is confined within a desirable range of movement by a pin 20 fixed at one end in the outer end portion of the latch and extending loosely through a hole in the 65 plate 16 adjacent the flange 17, said hole being countersunk and the head of the pin being shaped to enter, but not pull through, said hole. An expansive coil spring 21 is mounted on the pin 20 between the plate 70 16 and latch 18 and it is the function of said spring to separate the outer end of the latch from the plate and normally hold said latch within the groove 14 and in contact with the lug 15. Registering slots 22, 23 are formed 75 in the plate 16 and latch 18 respectively and a pull-key 24, having a lug 25 on one end, may be passed through the slots and engage the inner face of the latch for the purpose of contracting the latch on the plate by 80 manual operation to free said latch from the lug 15 and permit it and the plate to be withdrawn from the slide seat.

In practical use, the contents of the container are held and protected from accidental use by the arrangement of parts in the positions shown. When it is desired to remove contents from the container, said container is inverted, the key 24 is passed through the slots 22, 23 manually and the lug 25 is engaged with the latch and the latch is contracted on the plate and removed with said plate from the slide seat. This operation uncovers the stopper 13, and said stopper may then be withdrawn and contents be poured from the container manually. The key may be removed and the plate and latch be repositioned by opposite movement manually to cover the replaced stopper.

100 I claim as my invention—

1. A poison bottle or container having a discharge port, a stopper adapted to close said port, a plate slidably mounted in said container and adapted to confine said stopper, a latch disposed between said plate and container and normally engaging a part of said container, and means adapted to be passed through the plate and engage said latch, whereby said latch may be contracted 105 110 115

on the plate and removed therewith without injury to said container.

2. A poison bottle or container having a discharge port, a stopper adapted to close said port, said container being formed with a slide-seat, a plate slidably mounted in said seat and adapted to confine said stopper, a latch mounted on said plate adjacent said container, a spring between and acting on said plate and latch, said latch being adapted to engage a part of said container, and means for operating said latch to release against pressure of said spring without injury to said container.

15 3. In closing means for a poison bottle, a plate adapted to be mounted across the vent of said bottle, a leaf spring latch mounted thereon and normally separated at one end therefrom, said plate and latch being formed 20 with registering openings, and a hooked key adapted to be passed through said openings

and engage said latch, whereby said latch may be retracted toward said plate.

4. A poison bottle or container formed with a discharge port, and a slide-seat, and a groove in adjacent relation, a plate slidably mounted in said seat and extending across said port and groove, a latch mounted on said plate and spring-held in separation therefrom and adapted to enter said groove and engage said container, said plate and latch being formed with registering openings, and a key adapted to be passed through said registering openings and engage said latch, whereby the latch may be contracted 35 toward the plate and the latch and plate be removed from and without injury to the container.

Signed at Brawley, in the county of Imperial and State of California, this 3rd day 40 of February, 1920.

CHARLIE MOHME.
